US0D1013692S

(12) **United States Design Patent** (10) **Patent No.:** **US D1,013,692 S**
(45) **Date of Patent:** **** Feb. 6, 2024**

(54) **TABLET CARRYING DEVICE**

(71) Applicant: **UGOWEAR, LLC**, Prior Lake, MN (US)

(72) Inventors: **Melanie Cole**, Prior Lake, MN (US); **Vicky DeRouchey**, Prior Lake, MN (US)

(73) Assignee: **UGOWEAR, LLC**, Prior Lake, MN (US)

(**) Term: **15 Years**

(21) Appl. No.: **29/734,815**

(22) Filed: **May 15, 2020**

(51) **LOC (14) Cl.** **14-02**

(52) **U.S. Cl.**

USPC **D14/440**

(58) **Field of Classification Search**

USPC D14/440, 447, 250, 316; 361/679.55; 206/45.23, 320, 45.2; 294/25; 455/575.8; D3/289, 301, 283, 265, 243, D3/249, 294, 284, 274, 303, 266, 203.1, D3/315, 276

CPC ... G06F 1/1628; G06F 1/1626; A47B 23/044; A45C 11/00; A45C 13/02; H04B 1/3888

(57) **CLAIM**

The ornamental design for a tablet carrying device, as shown and described.

DESCRIPTION

FIG. 1 is a perspective view of the present design.

FIG. 2 is a front elevational view of FIG. 1.

FIG. 3 is a top view of FIG. 1.

FIG. 4 is a bottom view of FIG. 1.

FIG. 5 is a rear elevational view of FIG. 1.

FIG. 6 is a side profile view of FIG. 1; and,

FIG. 7 is an opposing side profile view of FIG. 1.

The broken lines are used to show unclaimed portions of the tablet carrying device and form no part of the claimed design.

1 Claim, 3 Drawing Sheets
